UNITED STATES PATENT OFFICE.

PETER SCHMID AND KARL GROSS, OF BASEL, SWITZERLAND; SAID GROSS ASSIGNOR TO
SAID SCHMID.

METAL-CHLORID BATH FOR WEIGHTING SILK.

1,193,429.

Specification of Letters Patent.

Patented Aug. 1, 1916.

No Drawing.

Application filed October 7, 1915. Serial No. 54,499.

To all whom it may concern:

Be it known that we, PETER SCHMID, a citizen of the Swiss Republic, and KARL GROSS, a subject of the King of Prussia, both residing in Basel, Switzerland, have invented a new Metal-Chlorid Bath for Weighting Silk, of which the following is a full, clear, and exact specification.

It is known that the weighting of silk is generally carried out by treating the silk alternately with metal chlorid baths (preferably with tin chlorid baths) and with alkali metal phosphate baths and finally with an alkali metal silicate bath. We have now found, that in this process a much greater and more regular weighting of the silk than hitherto is obtained, if the metal chlorid bath employed for weighting the silk contains dissolved silk and dissolved silkworm-chrysalises.

The present invention relates therefore to a metal chlorid bath for weighting, as for instance a zinc chlorid bath, a tin chlorid bath or a bath containing zinc chlorid and tin chlorid, and containing silk and silkworm-chrysalises in solution.

The silk to dissolve in the metal chlorid bath can be advantageously a silk waste, which already may contain silkworm-chrysalises, as for instance bassinets (Italian *gallettumini*, French *pelettes*).

The preparation of the new silk weighting bath is illustrated by the following examples:

Example I: In 2 liters zinc chlorid of 54° to 60° Baumé are introduced 100 grams pure silk and 100 gr. silkworm-chrysalises (these 200 gr. silk and chrysalises are dissolved in the zinc chlorid bath at a low temperature). To this solution is added the quantity of tin chlorid necessary to obtain a mixture containing equal quantities of both chlorids and this mixture is then diluted with water till a solution of 27 to 28° Baumé is obtained.

Example II: 100 gr. pure silk and 100 gr. silkworm-chrysalises are dissolved in 2 liters tin chlorid of about 27° Baumé. In this

example the tin chlorid can be replaced by zinc chlorid.

In all examples the indicated proportion of silk and chrysalises may be varied, also the proportion of tin chlorid and zinc chlorid in Example I can be varied.

In all examples the silk weighting bath can be prepared by substituting for the silk and the chrysalises the product obtained by boiling the same with water.

The new silk weighting baths are applied in the usual manner in liquid form to the silk, while the phosphate baths alternating with them may be employed in form of liquid or of froth. Obviously common salt and acid may be added where necessary to the silk weighting bath.

The use of the new silk weighting bath has the advantage that when a mixture of zinc chlorid and tin chlorid is employed for weighting silk, the same satisfactory results are obtained as by employing the more expensive tin chlorid alone. In all cases the silk weighted by use of the new metal chlorid bath shows a better affinity for the dye.

What we claim is:

1. A metal chlorid bath for weighting silk comprising a solution of at least one metal chlorid with silk and silkworm-chrysalises, the said metal chlorid being the chlorid of a metal able to be fixed on the silk fiber by an alkali metal phosphate bath.

2. A metal chlorid bath for weighting silk containing zinc chlorid, silk and silkworm-chrysalises in solution.

3. A metal chlorid bath for weighting silk containing zinc chlorid, tin chlorid, silk and silkworm-chrysalises in solution.

In witness whereof we have hereunto signed our names this 14th day of September 1915, in the presence of two subscribing witnesses.

PETER SCHMID.
KARL GROSS.

Witnesses:

ARNOLD ZUBER,
AMAND RITTER.
